UNITED STATES PATENT OFFICE

105,052

DESIGN FOR A CAR HEATER SHELL OR SIMILAR ARTICLE

Fred M. Young, Racine, Wis.

Application November 7, 1936, Serial No. 65,778

Term of patent 7 years

To all whom it may concern:

Be it known that I, Fred M. Young, a citizen of the United States, residing at Racine, in the county of Racine and State of Wisconsin, have invented a new, original, and ornamental Design for Car Heater Shell or Similar Article, of which the following is a specification, reference being had to the accompanying drawing which forms a part thereof.

The figure is a perspective view of a car heater shell, showing my new design.

I claim:

The ornamental design for a car heater shell or similar article, as shown.

FRED M. YOUNG.
